UNITED STATES PATENT OFFICE.

IRWIN MILTON THOMPSON, OF DE RIDDER, LOUISIANA.

BALE-BAND TIE.

1,095,946.

Specification of Letters Patent.

Patented May 5, 1914.

Application filed May 15, 1913. Serial No. 767,749.

To all whom it may concern:

Be it known that I, IRWIN M. THOMPSON, a citizen of the United States, and a resident of De Ridder, in the parish of Beauregard and State of Louisiana, have invented a new and Improved Bale-Band Tie, of which the following is a full, clear, and exact description.

The object of the invention is to provide a new and improved tie which may be quickly applied and removed, and formed so as to require the use of a minimum amount of material.

A further object of the invention is to provide a tie so formed that the band will hold the tie in place with only a slight assistance from a spur or projection extending from the tie into the bale, to which the tie is connected.

In carrying out these objects a blank is stamped out, formed with a body having a pair of apertures therein and a tongue extending from one side of the body formed with a bevel end or spur portion. The body is bent so as to extend at right angles to the tongue and is designed to have the bale band or wire passed through the aperture therein, while the tongue is designed to be bent in a general direction toward the body, but inclined to one side so as to cause the spur to enter the bale at one side of the portion of the tongue which joins the body.

A practical embodiment of the invention is represented in the accompanying drawings forming a part of this specification, in which similar characters of reference indicate corresponding parts in all the views.

Figure 1 is a perspective view of an embodiment of my invention shown applied; Fig. 2 is a top plan view of the structure shown in Fig. 1, a fragmentary portion of the bale being shown in connection therewith; Fig. 3 is a slightly enlarged perspective view of the tie just previous to the application thereof to the bale; and Fig. 4 is a top plan view of the blank.

Referring to the accompanying drawings by numerals, 1 indicate a bale of wood, though the tie may be applied to bales of various material. Surrounding the bale 1 is a band or wire 2 connected at its end with the tie 3. The tie 3 is formed with a body 4 bent at 5 so that aperture 6 will extend at substantially right angles to aperture 7. In applying the tie or wire 2 it is first passed through aperture 7 and then through aper-

ture 6 for a short distance, after which the main part of the wire is bent to the position shown in Fig. 1 and then passed around the bale so that the end 8 may be caused to properly engage the tongue 9. The tongue 9 extends from one side of the body 4, as more clearly shown in Figs. 2 and 4, and occupies approximately half the width of the body 4. This is desirable as it assists in permitting a maximum number of ties to be stamped out of a given sheet of material, and also permits the crown or spur 10 to be forced into the bale 1 at one side of the juncture of the tongue 9 and the body 4, as more clearly shown in Fig. 2, the spur being bent so as to enter the bale with the grain. It will be noted from the drawings that the tongue 9 is bent at 11, the bend being at an incline so that when the tongue 9 is bent over upon itself, the spur or prong 10 will not engage the body 4 or part of the tongue. The prong or spur 10 is merely a beveled or sharpened end of the tongue 9 bent at 12 to the correct angle for properly entering the bale. It will also be noted that the diagonally bending or positioning of the tongue causes the binding wire 2 to partially strain edgewise against the tongue whereby the tongue cannot be easily lifted.

From Fig. 1 it will be clearly seen how one end of the wire 2 is looped through the apertures in the body 4. The opposite end is wound around the tongue 9 at the bend 11 so that when the outer end of the tongue 9 is bent down to the position shown in Figs. 1 and 2, the wire will be clamped in position. In order to prevent any longitudinal slipping of the tie or wire 2, the prong or spur 10 is driven into the bale 1.

In forming the bale tie as described, it will be noted that the bending of the tongue 9 at an angle, as shown more particularly in Fig. 2, presents a structure in which the strain on the tongue is not directly in line with the bent over portion so that the diagonal bending of the tongue changes the direction of strain and thus relieves the tongue of part of the lifting or unbending strain. If the tongue 9 was bent directly back upon itself the strain on the wire or cable 2 would to a certain extent tend to unbend the tongue, but by the diagonal position of the tongue the strain is more in an edgewise direction against the tongue so that the unbending tendency is reduced to a minimum. This construction is of special

importance and advantage when tying bales of veneer as in cases of this kind the spur 10 can not be used as it will split the veneer. In instances of this kind the spur 10 is straightened out and the tongue 9 bent over to the position shown in Fig. 2, without the spur entering the bale. By the diagonal position of the bent over portion of the tongue the binding wire 2 will pull in a substantially edgewise direction against the tongue and especially against the bent over portion for properly holding the tie in position and holding the bale of veneer strips together.

Having thus described my invention, I claim as new and desire to secure by Letters Patent:

1. A bale tie comprising a plate formed with spaced apertures, a tongue extending from one end of the plate, said tongue being bent upon itself at a diagonal angle, and means projecting from the end of the tongue for entering the material being held, said means entering said material at one side of the juncture of the tongue and plate.

2. A bale band tie having a body portion bent intermediate its length, each of the bent portions of said body being formed with a band receiving opening, a tongue

projecting from the side of one end of said body, and a spur projecting from the end of said tongue, said spur being set at an angle to said tongue, and said tongue being bent upon itself and inclined to one side, whereby the spur will be positioned adjacent the juncture of the tongue and body portion, the angle of the spur in respect to the tongue being such as to cause the spur to extend parallel with the line of juncture of said bent portions of said body when the spur is in use.

3. A bale band tie, comprising a plate formed with a body designed to receive the end of a band, a tongue extending from one end of said body, said tongue being bent upon itself at a diagonal angle, and a spur projecting from the end of the tongue for entering the material being held, said spur entering said material at one side of the juncture of the tongue and plate.

In testimony whereof I have signed my name to this specification in the presence of two subscribing witnesses.

IRWIN MILTON THOMPSON.
